INVENTOR,

Robert H. Prichard
By *John W. Chapman*

HIS ATTORNEY.

UNITED STATES PATENT OFFICE.

ROBERT H. PRICHARD, OF LOS ANGELES, CALIFORNIA.

LUGGAGE CARRIER.

1,420,445.

Specification of Letters Patent. Patented June 20, 1922.

Application filed July 21, 1919. Serial No. 312,311.

To all whom it may concern:

Be it known that I, ROBERT H. PRICHARD, a citizen of the United States, residing at the city of Los Angeles, county of Los Angeles, State of California, have invented new and useful Improvements in Luggage Carriers, of which the following is a specification.

My invention relates to a luggage carrier for use on automobiles and the object thereof is to provide a carrier that is adjustable as to length and which can be quickly and easily attached to or detached from the running board of an automobile.

15 In the drawings forming a part of this application:

Fig. 1 is a side elevation of an automobile equipped with my carrier.

Fig. 2 is an enlarged side view of the carrier with a portion of the running board detached.

Fig. 3 is an end view of Figure 2.

Fig. 4 is a section on the line 4—4 of Figure 2.

25 Referring to the drawings 5 is a metal lazy tongs which forms the main body portion of my carrier. At the ends and intermediate thereof the lazy tongs is secured to U-shaped metal bars 6 which are 30 provided with longitudinal slots 7 in the lower portion thereof. At the top the connection between the lazy tongs and bars 6 is pivotal. The connection between the lazy tongs and bars 6 at the bottom is a sliding 35 one and is formed by passing heavy rivets 8 through the lazy tongs and slots 7 and heading them within the channels of bars 6. At the bottom bars 6 are slotted and clamps 9 are pivotally connected thereto by 40 rivets 10 so that when the clamps are secured to the running board 11 of the automobile 12 bars 6 and tongs 5 hold packages placed on the running board inside the tongs preventing them from slipping off the 45 running board. The clamps have shoulders 13 which prevent the bars from turning beyond the vertical when turning away from the machine. By this construction it will be seen that I have provided a carrier that

50 can be quickly attached to or detached from the running board of the machine, and one which can be adjusted as to length, and which can be folded down upon the running

board when not wanted for use, or can be removed therefrom and folded up and put 55 under a seat where it will take up very little room.

Having described my invention what I claim is:

1. A luggage carrier comprising a lazy 60 tongs, bars pivotally secured to one edge of the lazy tongs and slidably connected to the other edge of the lazy tongs, and clamps pivotally secured to said bars, some of said bars being at the ends and others intermediate 65 the ends of the lazy tongs, the bars intermediate the ends of the lazy tongs each being pivotally secured to the end joint of a pair of lazy tongs members, and slidably secured to the end joint of the pair of lazy 70 tongs members pivoted to the first pair.

2. A luggage carrier comprising a lazy tongs; U-shaped bars pivotally secured to one edge of the lazy tongs and slidably connected to the other edge of the lazy tongs; 75 and clamps pivotally secured to said bars, said clamps having shoulders to prevent the bars from turning more than ninety degrees.

3. In combination with a vehicle body 80 provided with a running board, of a lazy tong construction, a plurality of supporting standards pivotally attached at intervals to one edge of said lazy tong construction and slidably attached at intervals to the 85 other edge of said lazy tong construction, each standard being pivotally and slidably attached to the lazy tong construction, and a clamping means pivotally attached to the lower end of each of said supporting standards adapted to engage the vehicle running board to maintain said lazy tong construction in an extensible and rigid position, some of said standards being at the ends and other intermediate the ends 90 of the lazy tongs, the standards intermediate the ends of the lazy tongs each being pivotally secured to the end joint of a pair of lazy tongs members, and slidably secured to the end joint of the pair of lazy tongs 95 members pivoted to the first pair.

In witness that I claim the foregoing I have hereunto subscribed my name this 18th day of April, 1919.

ROBERT H. PRICHARD.
